UNITED STATES PATENT OFFICE.

J. FRANK WILCOMB, OF WORCESTER, MASSACHUSETTS, ASSIGNEE, BY MESNE ASSIGNMENTS, TO HEMPHILL COMPANY, OF CENTRAL FALLS, RHODE ISLAND, A CORPORATION OF MASSACHUSETTS.

METHOD OR PROCESS OF YARN OR THREAD MANIPULATION AND PRODUCT THEREOF.

Application filed December 17, 1919. Serial No. 345,514.

To all whom it may concern:

Be it known that I, J. FRANK WILCOMB, a citizen of the United States, and a resident of Worcester, in the county of Worcester and State of Massachusetts, have invented an Improvement in Methods or Processes of Yarn or Thread Manipulation and Product Thereof, of which the following description, in connection with the accompanying drawings, is a specification, like characters on the drawings representing like parts.

This invention relates to a method or process of yarn or thread manipulation which may be carried out in the production of a single cord or may be carried out in the production of knitted fabrics to be used for any desired purpose including hosiery, underwear, hand coverings and other articles.

My invention may be carried out by hand manipulation or suitable instrumentalities. It may also be carried out by mechanically operated parts involving or including certain instrumentalities to engage and act upon the yarn or thread in the formation of knitted loops. If a single set or pair of co-acting elements be employed, a single crocheted cord is produced. If a series of such elements are employed, a knitted fabric is produced.

While my invention is not limited in its scope or application to the use of any particular form or type of yarn engaging instrumentalities, I have obtained the best results by the use of a knitting instrumentality partaking of the general character of a knitting needle of that form herein shown. I shall therefore proceed to describe my method with particular reference to the carrying out thereof by or through the use of that form of instrumentality herein shown. It is, however, distinctly to be understood that while my invention is described with particular reference to such type of instrumentality, it may be otherwise practised within the broad scope and purpose of my invention.

In the drawings where I have represented a single type or embodiment only of the form of knitting instrumentality preferably employed:

Fig. 1 is a side elevation of a knitting instrumentality composed of two co-acting elements, said figure also showing a small

portion of the knitted fabric produced thereby;

Fig. 2 is a similar view, but representing the two co-acting elements in another relative position occupied at a subsequent portion of the knitting operation;

Fig. 3 is a similar view representing the two co-acting elements in still another relative position, and representing the next step in the knitting operation;

Fig. 4 is a similar view but representing the next succeeding step in the knitting operation;

Fig. 5 is a similar view but representing the co-acting elements as having returned to the position of Fig. 1;

Fig. 6 is a side elevation of a so-called stop member forming a part of one of the co-acting elements;

Fig. 7 is an end view of that one of the co-acting elements to which the stop member is applied;

Fig. 8 is a side elevation of one of the said co-acting elements and which I herein designate as the quill or sheath member of the needle unit;

Fig. 9 is a similar view of the other of said co-acting elements and which I herein designate as the hook member of the needle units;

Fig. 10 is a side elevation similar to Fig. 1 but indicating the manual manipulation or operation of the needle unit in the carrying out of my process or method; and

Fig. 11 represents the quill or sheath member as having a different form of point.

I will proceed to describe in detail that selected or preferred form of instrumentality or needle unit by which I may, and preferably do, practise my invention, without by such detailed description limiting in any way the application of my invention, it being understood that the instrumentality or needle unit may be employed, in manufacturing various forms or types of knitted fabric, in any desired number and in any desired relation to each other, as, for example, in a circular series vertically or otherwise arranged, or in one or two straight rows intersecting or otherwise where two rows are employed, or in a circular series intersecting or cooperating with another circular series arranged in a horizontal plane or otherwise

after the manner of a so-called rib knitting machine. A single instrumentality or needle unit may be employed in the production of a crocheted cord.

- 5 Referring more particularly to Figs. 1 to 9 inclusive, the knitting instrumentality in a single unit comprises two co-acting elements which I herein designate as a hook member 1 and a quill or sheath member 2.
- 10 The hook member as herein shown has a yarn hook 3, a throat 4, a butt 5 and a shank 6. The hook as herein shown preferably comprises the bend at the nose and the extended end portion which may be flexible or non-flexible as desired, all of which is embraced in the term "hook." The throat is the reduced part of the stem below the hook.

15 The quill or sheath member 2 is desirably of channel form, the side walls thereof being preferably thin and parallel. The end of the quill is pointed as indicated at 7 and is herein referred to as the nose, and may be bent, as shown in Figs. 1 to 8 and 10, or 20 straight as shown in Fig. 11. From such nose the edges of the side walls rise at 8 on an incline to the hump or swell 9, this being followed by edges reversely inclined with respect to the incline 8, as indicated at 10, 25 and leading to a throat 11. Herein below the throat 11 is the stem 12 which is preferably integral with or is connected with higher side walls 13 forming a base portion terminating with a lateral extension constituting the quill butt 14 and which may obviously be otherwise formed. Between the high walls 13 a block 15 may be rigidly positioned as by a rivet or rivets 16 or otherwise, thus forming a stop against which the 30 butt 5 contacts, thereby registering the hook with the quill swell. The block or stop desirably has a butt portion, and it is herein shown as of less depth than the walls 13 to afford a continuation of the channel of the 35 quill serving to hold the needle shank and needle in the quill.

40 Obviously the stop 15 may be brazed, welded or otherwise secured in place and may be of any suitable form that will register the needle hook with the quill hump or swell.

45 If desired and in the mechanical operation or carrying out of my method, the two co-acting members or elements of the needle unit, of which any desired number and arrangement may be provided, are operated by cams, desirably one for each set of such members or elements, said cams if provided acting upon the butts of the members or elements in a manner that need not be described in detail.

50 Referring now to Figs. 1 to 5 which show the co-acting elements or members of the needle unit in the different positions assumed 55 thereby during the knitting operation and

the carrying out of my method, Fig. 1 represents the elements of the unit in their retracted position with the loop 17 hanging or positioned in the hook of the hook member of the unit.

70 Fig. 2 represents the hook member 1 as having advanced in relation to the quill or sheath member 2 so as to open the hook 3 for receiving the new yarn, or rather, that portion of the yarn providing the new loop.

75 Fig. 3 represents the hook member 1 as still further advanced but followed by the quill member 2 so as to maintain substantially the same relation to each other as in Fig. 2. In that relation of the two members 80 or elements indicated in Fig. 3, the quill member 2 has passed into the old loop indicated in said figure at 17^a, and the said old loop 17^a has ridden up the incline 8 over the swell 9 and has lodged in the throat 11 of the 85 quill member as clearly indicated in said figure. The new yarn has been supplied to the hooked portion of the needle as indicated at 18 in Fig. 3.

90 The elements or members of the needle unit are now retracted to the position and into the relation of parts indicated in Fig. 4 wherein the hook 3 is closed by reason of the fact that its hook enters between the walls of the swell 9 of the quill element or 95 member, so that the old loop 17^a may be cast off, which is done when the parts, continuing their retraction while in the relation indicated in Fig. 4, have reached the position 100 indicated in Fig. 5. In said Fig. 5 the old 100 loop 17^a is represented as incorporated into the substance or body of the knitted fabric and the succeeding loop 18 is now held in the hook 3, being confined therein by the 105 walls of the swell 9.

110 It is unnecessary for me to represent other parts of a knitting organization that may be employed if desired in the mechanical carrying out of my method. I, however, state that in such mechanical carrying out of 110 the method I may employ yarn feeding sinkers either for ribbed work using two rows or sets of needle units, or for flat work made upon single rows or sets of needles. The needle unit composed of the co-acting elements of the general type or form herein disclosed is neither a latch needle nor a 115 spring beard needle. It is unnecessary to set forth in detail the various characteristic differences between the needle unit preferably employed by me in the practice of my method and latch needles and spring beard needles. I may, however, briefly point out that in the practice of my method I avoid entirely the use of the latch of the latch needle with the consequent difficulties and evils incident thereto, and I desirably avoid the objections due to crystallization of the beards of spring beard needles, the side deflection of said beards, and fatigue 120

125 130

causing "dead" beards. I also dispense with needle pressers. Latch guards and latch openers such as are commonly used with latch needles are not required.

5 In the practice of my invention so far as processes and mechanisms involving direct feeding to the needles are concerned and as an important step in the carrying out of my method, I effectively divide the new yarn or 10 the new strand thereof and the old or fabric loop, and I do this in a simple, safe and reliable manner, whereas in the case of spring beard needles attempted division of the 15 yarns or succeeding loops upon the same needle has been largely a matter of skillful adjustment of mechanical devices by a knitting expert. My invention is particularly well suited to sinker knitting, obviously without being limited thereto, and may be 20 practised in processes or organizations wherein sinkers are employed to sink the yarn with great saving of needle travel and the non-use of beard pressers.

The throat of the hook member or element 25 of the needle unit, preferably employed in practising my method, is smaller and thinner than in ordinary needles by an amount equalling the thickness of the walls of the quill member. It is obvious that all loops 30 in a knitting operation pass over the largest part of the needle or knitting instrumentality, which in the latch type of needle comprises the hook and closed latch thereof.

Referring now to the formation of loops 35 in accordance with my process and more particularly by the use or action of a series of co-acting elements of the herein-described type in the production of fabric, it is evident that a loop large enough to pass over 40 the hump or swell 9 will hang on the throat of the needle in the form substantially indicated for example in Figs. 2 and 5, assuming that fabric-tension exists, and thus a relatively large opening or loop is exposed 45 at the back of the stem of the hook member, and hereinafter referred to as the normal loop opening, and through which relatively large opening or loop the quill nose 50 of the forms shown in the drawings can pass freely as indicated by Figs. 2 and 5. The size and shape of this opening depend upon several factors among which may be 55 enumerated the presence or absence of fabric take-up tension. I will herein refer to the loop opening as the normal loop opening without thereby limiting myself to any particular size or shape thereof, since it is obvious that in the absence of fabric-tension, the walls of said loop may at certain stages 60 of the operation lie quite close against the back of the needle in a non-opened or non-spread condition.

An important feature or step of my method flows from such normal loop opening, and is taken advantage of by me in the

effective practice of my method. Referring now to the form of instrumentality shown in the drawings, it will be observed that in Figs. 2 and 3 the nose of the quill member or element initially enters the normal loop 70 opening at the rear of the stem of the hook member 1. The formation of the normal loop opening as diagrammatically indicated at 19 in Fig. 2, and which is a necessary characteristic of a knitted loop, is availed of 75 by me in the carrying out of my method and so far as I am aware, for the first time in the art, by causing a casting off element of a needle unit, or a cooperating member of a pair of co-acting elements, to enter said normal loop opening initially at an unstressed 80 part thereof at the rear of the point where the said loop is supported and to spread the loop by forcing the yarn outwardly toward or with reference to the point of loop support. 85

While for purposes of concrete explanation I have described the last formed loop as supported upon a hooked instrument of the form shown, it is obvious that for the purpose and within the broad scope of my invention the loop may be supported in any suitable manner. Such a supported loop 1, in the preferred practice of my invention, cause to be entered by a part, device or co-acting element at the normal opening therein between the point of support of the loop and the throat of the loop, this being done in the disclosed embodiment of means whereby my invention may be practised, by 100 the other co-acting member of the needle unit.

Where the co-acting member entering the normal loop opening between the point of support of the loop and the throat thereof 105 is of that preferred character represented in Fig. 8, it is evident that the two parallel walls of the rise 8 engage the yarn of the loop at the sides of the hook member 1 so as to force the yarn outwardly in a forward 110 direction, that is, forwardly toward or with reference to the point of loop support. Said point of loop support is herein shown as at the front of the hook member 1 and the said rise 8 and the subsequently acting swell 9 115 may and preferably do open or spread the loop by acting thereon after entering the normal loop opening. The contact of the rise 8 and swell 9 with the yarn being at the sides of the hook member 1 is therefore at 120 parts of the yarn loop which are comparatively unstressed, as opposed to that portion of the yarn where the loop is supported as upon the hook 3 and where it is under the greatest stress. Such opening or spreading 125 may temporarily borrow yarn from the adjacent loops in order to pass the swell 9, but it is not intended so to expand the loops as to rupture the yarn fibres.

The two parallel walls of the quill mem- 130

ber or element cause the spread or opened loop, which at such time is under stress, to pass more freely and with less liability of rupture over the hook of the hooked member or element than would be the case with latch needles where a single latch having a thickness of about .005 has a decided cutting tendency on the yarn as the angle of the yarn in such case is a very acute angle, whereas the said parallel walls of the quill member or element hold the yarns always at a right angle.

In the practice of my invention wherein yarn is suitably fed with sinkers, I position and support yarn or thread in a series of fabric loops in a single course and so that, with fabric-tension, a normal loop opening is presented between the throat of each of said loops and the opposite or support end thereof. I thereupon enter or engage, and desirably mechanically, each of the said loops at the said normal loop opening thereof between the throat thereof and the point of support of the loop at the opposite end 25 of the loop and I open or spread each of said loops, and preferably by force applied outwardly in a forward direction toward the point of loop support. In the preferred practice of my invention I open or spread the loops both laterally and forwardly, but mainly forwardly, with respect to the point of support thereof. I thereupon separate or divide each of said opened or spread loops from the new yarn extending across the 35 needle stems, as by sliding the opened or spread loops back of the swell 9, and then I guard the hook of the yarn drawing instrument by the swell, cast off the spread of opened old loop, over said guarded hook, and draw the new loop through this cast off loop.

In practising this method I preferably in the formation of a fabric employ a series of pairs of co-acting elements, one element of each pair having a hook or loop-supporting part or formation and the other element having a part to enter the loop in the rear of its point of support. In practising this method with the use of co-acting elements 50 of such general character, I position the yarn on a series of yarn drawing instruments having hook or other yarn supporting and drawing formations and suitably feed the yarn thereto. I position the fabric loops of the yarn so that each loop is engaged or supported on the stem or body portion of the instrument and so that the throat of each loop is at the rear of said stem or body portion and whereby with fabric-tension a normal loop opening is presented between said 55 throat and the stem or body of the instrument. I thereupon penetrate each loop at said normal loop opening between its throat and the stem or body portion of the hooked 60 instrument and preferably by a casting off 65

instrument, and thereby open or spread such loop. Such opening or spreading of the loop is effected desirably forwardly, and it may be, subordinately, laterally with reference to the point of support of each loop. 70 I then separate or divide each so penetrated old loop from the new yarn lying across the needle stem, by a portion of the casting off instrument, whereby ample space is provided between the old loop and the new yarn 75 for positioning the hook end between them and whereby also the old loop is placed beyond the reach of said hook. I then guard the hook of the yarn drawing instrument by the swell formation 9 and at the same time 80 imprison the new yarn in the hook and then I cast the opened old loop over said hook and draw the new yarn therethrough. As hereinbefore stated, this recitation of sequence of steps is not a limitation to said 85 steps as carried out in such sequence.

In the practice of my method and particularly in carrying out the same by instrumentalities substantially such as disclosed herein, the loops are opened or spread by the application of pressure outwardly, preferably in a forward direction upon both sides of said loops and first at points spaced from where the loops are stressed across the front of the yarn drawing instruments, and then I progressively bring successive portions of the loop sides between said spaced points and the supported end of each loop under the said opening or spreading action.

Within the scope and purpose of my invention it is not requisite though it is desirable, that all the steps of the method be practised in conjunction, since certain steps of the invention as for example, the penetration of the normal loop opening and the opening or spreading of the loop may be practised whether or not the loops are divided or separated in accordance with the preferred mode of practising my invention.

I desire it clearly to be understood that my invention is not limited either to sinker knitting or to direct feed knitting, and the specification and claims are to be interpreted accordingly.

Wherever in the claims a series of loops is mentioned in connection with loop spreading or other actions taking place thereon, such statement applies to loops formed either seriatim along the series or to a number of loops formed simultaneously. I do not herein claim as a structure the knitting needle unit and machine organization, since the same is disclosed and claimed in my co-pending application Serial No. 289,691, filed April 12, 1919, the present application being directed to a method or process in the carrying out or practice of which such needle unit may be employed.

Having thus described the best mode known to me for practising my invention

and one specific embodiment of means whereby if desired it may be carried out, I desire it to be understood that I have employed terms in a generic sense and not for purposes of limitation, the scope of the invention being set forth in the following claims.

Claims:

1. That method of knitting comprising the following steps: positioning and supporting a series of fabric loops in a single course so that with fabric-tension a normal loop opening is presented between the throat of each of said loops and the opposite end or point of support thereof; engaging each of said loops at said normal loop opening for loop-spreading or opening and spreading or opening such loop by force applied forwardly within the loop from the place or zone of engagement; feeding yarn or thread for the next or new loops; casting off the first mentioned or old loops over the next or new series of loops and drawing sufficient yarn for the said next or new loops.
  2. That method of knitting comprising the following steps: positioning and supporting a series of fabric loops in a single course so that with fabric tension a normal loop opening is presented between the throat of each of said loops and the opposite end or point of support thereof; effecting entrance into each of said loops of said normal loop opening for loop-spreading or opening and spreading or opening such loop by pressure outwardly in a forward direction toward the point of loop support; feeding yarn or thread for the next or new loops; casting off the first mentioned or old loops over the next or new series of loops, and drawing sufficient yarn or thread for the said next or new loops.
  3. That method of knitting comprising the following steps: positioning and supporting a series of fabric loops in a single course so that with fabric tension a normal loop opening is presented between the throat of each of said loops and the opposite end or point of support thereof; engaging each of said loops at said normal loop opening for loop-spreading or opening and spreading or opening such loop by force applied forwardly within the loop from the place or zone of engagement; feeding yarn or thread for the next or new loops; separating or dividing each of said loops from the new yarn; casting off the first mentioned or old loops over the next or new series of loops; drawing sufficient yarn for the said next or new loops.
  4. That method of knitting comprising the following steps: positioning and supporting a series of fabric loops in a single course so that with fabric tension a normal loop opening is presented between the throat of each of said loops and the opposite end
- or point of support thereof; effecting entrance into each of said loops at said normal loop opening for loop-spreading or opening and spreading or opening such loop by force applied outwardly in a forward direction toward the point of loop support; feeding yarn or thread for the next or new loop; separating or dividing each of said loops from the new yarn; casting off the first mentioned or old loops over the next or new series of loops, and drawing sufficient yarn for the said next or new loops.
5. That method of knitting which embraces the following steps: positioning and supporting a series of completed loops in a single course; engaging each loop at the back of its support and exerting pressure outwardly from within the same from the back of the support to the front of the loop; feeding new yarn; casting off the so-engaged loops from their supports and drawing the new loops therethrough.
6. That method of knitting which embraces the following steps: so positioning a series of loops in a single course and supporting them as, with fabric tension, to leave openings therethrough at the back of the loop supports; spreading the loops by exerting pressure outwardly and forwardly from within the same at the back of the supports; casting said spread loops off from their supports; and drawing the new loops through the cast loops.
7. That method of knitting which embraces the following steps: positioning and supporting a series of completed loops in a single course; engaging each loop at the back of its support for loop-opening or spreading and opening or spreading the loop by exerting pressure outwardly from within the same from the back of the loop support to the front thereof; feeding new yarn; casting off the spread loops from their supports, and drawing the new loops therethrough.
8. That method of knitting which embraces the following steps: positioning and supporting a series of completed loops in a single course; engaging each loop at the back of the loop support for loop-opening or spreading and opening or spreading each loop by exerting pressure outwardly from within the same from the back of the loop support to the front of the same; feeding new yarn or thread for the next or new loops; separating or dividing each of the said loops from the new yarns; and casting off the spread loops from their supports, and drawing the new loops therethrough.
9. That method of knitting comprising the following steps: positioning and supporting a loop so that a normal loop opening is presented between the throat of said loop and the opposite end or point of support thereof; engaging said loop at said nor-

- mal loop opening for loop-spreading or opening and spreading or opening said loop by force applied forwardly within the loop from the place or zone of engagement; feeding the yarn or thread for the next or new loop; casting off the first mentioned or old loop over the next or new loop; and drawing sufficient yarn for the said next or new loop.
10. That method of knitting comprising the following steps: positioning and supporting a loop so that a normal loop opening is presented between the throat of said loop and the opposite end or point of support thereof; effecting the entrance into said loop at said normal loop opening for loop spreading or opening and spreading or opening such loop by pressure outwardly in a forward direction toward the point of loop support; feeding yarn or thread for the next or new loop; casting off the first mentioned or old loop over the next loop; and drawing sufficient yarn or thread for the said next loop.
15. That method of knitting comprising the following steps: positioning and supporting a series of fabric loops in a single course; opening or spreading each loop by exercising pressure outwardly from within the same between the throat of each loop and the point of support thereof; feeding yarn or thread for the next or new loops; casting off the first mentioned or old loops over the new or next series of loops; and drawing sufficient yarn for the said new or next loops.
20. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; separating or dividing each of said first mentioned or old loops from the new yarn; casting off the said first mentioned or old loops over the new or next series of loops, and drawing sufficient supply of yarn for the new or next loops.
25. That method of knitting comprising the following steps: positioning and supporting a series of fabric loops in a single course; separating the two sides of each of said loops by exerting pressure outwardly upon said two sides; feeding yarn or thread for the next or new loops; separating or dividing each of the first mentioned or old loops from the new yarn; casting off said first mentioned or old loops over the new or next series of loops and drawing sufficient yarn for the next or new loops.
30. That method of knitting comprising the following steps: positioning and supporting loops of a series of loops on a series of hooked yarn draw-
- ing instruments; opening or spreading said loops by exerting pressure outwardly upon both sides of said loops and first at points spaced from where they are stressed across the front of the yarn drawing instruments; and then progressively bringing successive portions of the loop sides between said points and the supported end under said opening or spreading action; feeding yarn or thread for the next or new loops; casting off said opened or spaced loops and drawing the new loops therethrough.
35. That method of knitting comprising the following steps: positioning loops of a series of loops on a series of hooked yarn drawing instruments; initiating the spreading or opening of said loops by applying outward pressure upon the sides at the point where the normal loop opening is exposed at the back of the yarn drawing instrument and continuing said spreading or opening action progressively at both sides of the loop toward its end where it is stressed across the yarn drawing instrument; feeding yarn or thread for the next or new loops; casting off said loop and drawing the new loop therethrough.
40. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; separating or dividing each of said first mentioned or old loops from the new yarn; casting off the said first mentioned or old loops over the new or next series of loops, and drawing sufficient supply of yarn for the new or next loops.
45. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; casting off the said first mentioned or old loops over the new or next series of loops, and drawing sufficient supply of yarn for the new or next loops.
50. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; casting off the said first mentioned or old loops over the new or next series of loops, and drawing sufficient supply of yarn for the new or next loops.
55. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; casting off the said first mentioned or old loops over the new or next series of loops, and drawing sufficient supply of yarn for the new or next loops.
60. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; casting off the said first mentioned or old loops over the new or next series of loops, and drawing sufficient supply of yarn for the new or next loops.
65. That method of knitting comprising the following steps: positioning and supporting a series of fabric loops in a single course so that with fabric-tension a normal loop opening is presented between the throat of each of said loops and the opposite end or point of support thereof; engaging, for loop-spreading or opening each of said loops between the throat thereof and the point of support at the opposite end of such loop and spreading or opening such loop by force applied at the sides of the loop between the said throat and the opposite end thereof; feeding yarn or thread for the next or new loops; casting off the said first mentioned or old loops over the new or next series of loops, and drawing sufficient supply of yarn for the new or next loops.

18. That method of knitting comprising the following steps: positioning and supporting a series of fabric loops upon a series of instruments having yarn receiving and supporting formations, so that the throat of each loop is at the rear of the point of support of such loop and so that with fabric-tension a normal loop opening is presented between said throat and said point of support of such loop; mechanically engaging each of said loops between its throat and the point of support of such loop and continuing such mechanical engagement so as to spread or open the loop by engagement between its throat and the point of support thereof; separating or dividing each of the first mentioned or old loops from the new yarn, whereby each old loop is projected from the yarn receiving and supporting formation of such instrument; feeding yarn or thread for the next or new loops; casting off the said first mentioned or old loop over the yarn receiving and supporting formation of said instrument while retaining the new loop imprisoned by said yarn receiving and supporting formation; and drawing sufficient supply of yarn for the new or next loops.
19. That method of knitting comprising the following steps: positioning and supporting a series of fabric loops in a single course and so that with fabric-tension a normal loop opening is presented between the throat of each of said loops and the opposite end or point of support thereof; engaging, for loop-spreading or opening each of said loops at said normal loop opening between the throat thereof and the point of support at the opposite end of such loops and spreading or opening such loop by force applied to the yarn of the loop between the said throat and the opposite end thereof; feeding yarn or thread for the next or new loops; separating or dividing each of said first mentioned or old loops from the new yarn, casting off the said first mentioned or old loops over the new or next series of loops; and drawing sufficient supply of yarn for the new or next loops.
20. That method of knitting comprising the following steps: positioning and supporting a series of loops in a single course of loops and so that with fabric-tension a normal loop opening is presented between the throat of each of said loops and the opposite or support end thereof; engaging each of said loops at said normal loop opening between the throat thereof and the point of support at the opposite end of said loop and spreading or opening such loop; feeding yarn or thread for the next or new loops; casting off the first mentioned or old loops over the new or next series of loops and drawing sufficient supply of yarn for the new or next loops.
21. That improvement in the art of knitting which consists in opening the supported loops by progressively engaging the sides of the loops toward the looped or closed front ends thereof.
22. That improvement in the art of knitting which consists in opening the supported loops by first contacting them at points in the rear of the closed supported portions thereof and continuing said opening action progressively toward the said closed front ends.
23. That improvement in the art of knitting which consists in forming a series of loops supporting said loops preparatory to drawing others therethrough and opening said loops for the reception of said others by first engaging them at other than the points of support.
24. That improvement in knitting fabrics which consists in knitting the same with the loops interengaging without stretching the closed ends of the loops by the drawing of the contained loops therethrough.
25. The fabric resulting from said method, the same comprising interengaging loops, the closed ends whereof have been unstretched by the drawing of the contained loops therethrough.
26. That improvement in the art of knitting which consists in initiating the spreading of the loop at a point spaced from the point where said loop is supported.
27. That improvement in the art of knitting which consists in initiating the spreading of the loop at a point spaced from the point where said loop is supported and completes the spreading thereof toward said point of support.
28. That improvement in the art of knitting which consists in opening the supported loops by first entering and engaging the loops at unsupported points thereof.

In testimony whereof, I have signed my name to this specification.

J. FRANK WILCOMB.
